Primary Examiner—Lucy Lieberman**Attorney, Agent, or Firm**—Dennis W. Braswell**[57] CLAIM**

The ornamental design for a bottle, as shown and described.

DESCRIPTION

FIG. 1 is a top left side perspective view of a bottle showing my new design;

FIG. 2 is a front elevational view thereof;

FIG. 3 is a left side elevation, the right side elevation is a mirror image thereto;

FIG. 4 is a rear elevational view thereof;

FIG. 5 is a top plan view thereof; and,

FIG. 6 is a bottom plan view thereof;

The broken lines in the drawings are for illustrative purposes only and do not form part of the claimed design.
